UNITED STATES PATENT OFFICE

JAMES R. DEVOR, OF GOSHEN, INDIANA, ASSIGNOR OF ONE-HALF TO
EDWARD S. NORTON, OF ST. PAUL, MINNESOTA.

PRESS.

SPECIFICATION forming part of Letters Patent No. 269,922, dated January 2, 1883.

Application filed October 31, 1882. (No model.)

To all whom it may concern:

Be it known that I, JAMES R. DEVOR, a citizen of the United States, residing at Goshen, in the county of Elkhart and State of Indiana, 5 have invented a new and useful Press, of which the following is a specification, reference being had to the accompanying drawings.

Figure 1 is a plan view of my improved press with parts broken away so as to show the construction. Fig. 2 is a vertical cross-section on the line *x x*, Fig. 1. Fig. 3 is a vertical sectional view on the line *y y*. Fig. 4 is a detail view of a section of the track, and Fig. 5 is a detail view of one of the partition-plates or 15 diaphragms.

Corresponding parts in the several figures are denoted by like letters of reference.

This invention relates to an improved machine for pressing and solidifying bran and 20 other similar matter into blocks or cakes which may be readily handled and marketed; and it consists in the improved construction of said press, which will be hereinafter fully described, and particularly pointed out in the claims.

25 In the drawings hereto annexed, A represents the base of the machine, which is circular, as shown, and has a circular track, B, consisting of Δ -shaped rails, which support several sets of V-grooved wheels, C, connected 30 in pairs by shafts or axles D.

E are two concentric rings, the under sides of which are V-shaped, so as to enable them to rest, as shown, upon the wheels C. The inner sides of the rings E have shoulders F, 35 supporting a large circular trough or box, G, which forms the press-box. The outer sides of said rings have flanges H, the upper sides of which are provided with teeth or cogs I. The bottom of the box or trough G has transverse 40 or radial openings or slots J, in which are fitted the vertically-sliding partition-plates or diaphragms K, which are provided at their ends with vertical guides L, moving in recesses M in the sides of the box or trough.

45 The plates K are provided with downward-projecting stems N, extending through brackets O under the bottom of the box. Springs P are coiled upon said stems between the brackets O and the bottom of the box, said 50 springs serving to force the partition-plates or

diaphragms in an upward direction till their upper edges are level with the top of the box.

The upper ends of the guides L, which project above the top of the box, may be rounded or provided with friction-rollers Q.

55

R is a large roller, mounted upon a shaft, S, transversely over the box G, in which the said roller R is nicely fitted some distance above the bottom. The shaft S has its bearings in brackets or uprights T at the sides of the box 60 or trough, and said shaft is provided with gear-wheels U, meshing with the teeth or cogs I upon the flanged rings E. By this construction, when the shaft S revolves the gear-wheels U, engaging the cogs I, cause the flanged rings 65 E, supporting the box or trough G, to revolve in a horizontal plane under the roller R. The brackets or uprights T also support an inclined plane, V, fitted nicely between the sides of the press box or trough, with its upper end 70 rounded or beveled and placed closely in contact with the roller R. Said inclined plane serves, in conjunction with the press-box, to compress the material placed in the latter. The lower end of the inclined plane V of course 75 terminates a distance above the bottom of the press-box equal to the thickness it is desired to make the blocks or cakes.

W is another inclined plane parallel to V, and arranged above the press-box just in rear 80 of said plane V. The plane W is of such width as to act upon the friction-rollers Q at the upper ends of the guides L of the vertically-moving diaphragms K. The latter, it will be observed, have, by passing under the plane V, 85 been forced down to within a short distance of the bottom of the press-box, and the plane W is so arranged in relation to the said diaphragms as to force them down flush with the bottom of the press-box.

90

X is a third inclined plane, the lower or front end of which rests upon the bottom of the press-box just below the point at which the inclined plane W terminates. Its upper end is placed in contact with an endless belt or apron, 95 B', mounted upon suitable rollers in a tangential position in relation to the press-box, and serving to carry the pressed material away from the press.

The material to be pressed is fed into the 100

box G just in front of the roller or cylinder R through a spout, Y, or in an suitable convenient manner.

When the revolving trough or press-box is sufficiently large two or more sets of the compressing rollers, inclined planes, and other mechanism may be used in connection with it, as illustrated in the drawings, where four such sets have been shown, making a continuously-acting quadruple press of great power and capacity.

Motion may be imparted to the drive-shafts S in any suitable manner—for instance, as in the drawings—from a centrally-located master-wheel, Z, engaging gear-wheels A' upon the inner ends of the shafts S.

From the foregoing description, taken in connection with the drawings hereto annexed, the operation and advantages of my invention will be readily understood. The material enters the press-box in front of roller R, by which it is compacted or packed in the compartments formed by the diaphragms K, which latter are also forced downwardly by the said roller. The inclined plane V serves to compress the material which is forced or fed under it by the diaphragms K. The latter are then, by the action of the inclined plane W, forced down flush with the bottom of the box, from which the compressed material is then removed by the inclined plane X and belt or apron B'.

I claim and desire to secure by Letters Patent of the United States—

1. The circular horizontally-revolving press box or trough, having vertically-sliding transverse partitions or diaphragms, in combination with suitable compressing mechanism, and means for removing the compressed matter from the press-box, as set forth.

2. The circular horizontally-revolving press

box or trough, having vertically-sliding transverse partitions or diaphragms, in combination with the roller or cylinder R, inclined plane V, and mechanism for depressing the diaphragms flush with the bottom of the press-box, as set forth. 45

3. The combination of the base A, having track B, the V-grooved wheels C, the rings E, having V-shaped under sides, shoulders F, and toothed flanges H, and the press-box G, as set forth. 50

4. The combination of the press-box G, having recesses M, and brackets O, with the vertically-sliding diaphragms K, having guides L, provided with friction-rollers Q, and stems N, 55 the springs P, and the inclined plane W, as set forth.

5. The combination of the rings E, having toothed flanges H, the press-box G, having vertically-sliding diaphragms K, the shaft S, 60 having roller R and gear-wheels U, and suitable operating mechanism, as set forth.

6. The combination of the revolving press-box having vertically-sliding diaphragms, the roller R, inclined planes V, W, and X, arranged 65 as herein described, and the endless apron or belt B', as and for the purpose set forth.

7. The combination of the circular horizontally-revolving press-box, the radial shafts S, carrying compressing-rollers R, and a centrally-located master-wheel engaging gear-wheels 70 upon the inner ends of the said shafts S, as set forth.

In testimony that I claim the foregoing as my own I have hereunto affixed my signature 75 in presence of two witnesses.

JAMES ROWLAND DEVOR.
